(57) **CLAIM**

The ornamental design for a handle for an ink cartridge, as shown and described.

DESCRIPTION

The design is embodied as a handle for an ink cartridge which contains ink for use in an ink jet printer.

FIG. 1 is a perspective view illustrating the front, bottom and right side of a handle for ink cartridge showing our new design;

FIG. 2 is a perspective view of the rear, top and right side thereof;

FIG. 3 is a front elevational view thereof;

FIG. 4 is a rear elevational view thereof;

FIG. 5 is a top plan view thereof;

FIG. 6 is a right side elevational view thereof; and,

FIG. 7 is a left side elevational view thereof.

The broken lines are for illustration only and form no part of the claimed design.
